UNITED STATES PATENT OFFICE.

ANDREW CAMPBELL, OF NEWCASTLE, NEW SOUTH WALES, AUSTRALIA, ASSIGNOR
TO THE BROKEN HILL PROPRIETARY COMPANY, LIMITED, A CORPORATION OF
THE STATE OF VICTORIA, AUSTRALIA.

OPEN-HEARTH FURNACE.

Application filed January 28, 1922. Serial No. 532,520.

To all whom it may concern:

Be it known that I, ANDREW CAMPBELL, a subject of the King of Great Britain, residing at Maryville, Newcastle, New South Wales, Australia, have invented a new and useful Open-Hearth Furnace, of which the following is a specification.

The invention relates to open hearth furnaces. The object is to provide improved method and means for controlling the temperature of one or more of the regenerators independently of the other regenerators, or at least independently of the usual means for controlling the temperature of the other regenerators, preferably the air regenerators independently of the gas regenerators.

The invention comprises the method and means for increasing the draft through one of the regenerators relatively to that of another regenerator, or for controlling the draft so as to increase or decrease the pressure in the waste gases passing through one or more regenerators to the stack. This may be done conveniently by connecting an air regenerator directly with the stack, independently of, or in cooperation with, the means for reversing the flow between the regenerators and the stack.

Referring to the drawings which represent, merely by way of example, suitable means for effecting my invention:

Fig. 1 is a plan, in diagram, representing the gas regenerators and the air regenerators and the flues and ports for connecting the same with the stack.

Fig. 2 is a diagram, in section indicating the valve control for the flues or passages.

Similar numerals indicate similar parts in the different views.

The gas regenerators 1 and 2 are of the usual checker construction, as are likewise the air regenerators 3 and 4. These regenerators have the usual connections to the combustion chamber or furnace, and the usual connections and controls for the air and gas supply. Such connections and controls are not shown, because they may be in accord with the common practice and they form no part of the present invention. The air regenerators 3 and 4 are connected to the flues or passages 7 and 8 respectively. The flue or passage 9 leads directly to the stack 10. The flues or passages 5 and 6 are provided with the ports 11

and 12 respectively. The flues or passages 7 and 8 are provided with the ports 13 and 14 respectively. The flue or passage 9 is provided with the ports 15 and 16. This flue or passage 9 is also in open communication with the space or chamber 17. Communication between flue 7 and flue 8 and chamber 17 is controlled by any suitable valves, such as 18 and 19. Communication between ports 13, 14 and 16 and ports 11, 12 and 15 is controlled in the usual way by any suitable form of reversing valve, such for example, as the valve 20, actuated by the piston 21, operating in cylinder 22.

It is common and well known practice to provide means for automatically connecting the regenerator port, which is disconnected from the stack port, with the gas or air supply, as the case may be. It is also common practice to supply such further controlling valves as may be desired. Such devices are not shown in this present application, since they are assumed and form no part of the present invention.

This method of controlling and reversing the direction of flow of air and gas through the regenerative chambers, by first establishing communication between one set of flues, such as 5 and 7, and the stack, and then interrupting such communication, and establishing communication between the other set of flues, such as 6 and 8, and the stack is common practice and well understood in the art.

It happens however that, at the beginning of a run, when the checker work of the air regenerator is comparatively clean and unobstructed, the passage of burnt products therethrough is comparatively free, but, as the run progresses, the passages through the checker work become more or less clogged or obstructed by the accumulation of dust and the like, carried over from the furnace. This undesirable condition increases as the run progresses, and thus, under ordinary circumstances, the efficiency of regenerative action of the chamber becomes impaired. It is therefore the practice that when these regenerators become so clogged that the efficiency of the furnace is reduced to such an extent that the cost of operation is excessive, the furnace is allowed to cool down and the regenerators are cleared out either by steam or air jets, or by the removal of the checkers

and cleaning of same by hand and replacement by new bricks where necessary.

I have found that these extensive delays to furnace operations are overcome by a very simple and effective method, and the efficiency of the furnace maintained without impairment as long as the roof of the furnace lasts, or until extensive general repairs are required necessitating the cooling off of the furnace. This consists in providing a space such as chamber 17, or its equivalent, which, as above stated, is in free and open communication with the stack flue 9, and means for by-passing the flow from flue 7 or 8, independently of the usual reversing valve control of communication between the regenerator flues and the stack.

The communication between flues 7 and 8 and chamber 17, which is controlled by any suitable form of valves, 18 and 19, is preferably a regulatable control. This permits of a flow from the air regenerator flue to the stack entirely through chamber 17, or it may be in conjunction with the flow through the reversing valve or valves, controlling ports 11, 12 and 15, and 13, 14 and 16. In this way as the air regenerator becomes more and more obstructed the efficiency of communication between said regenerator and the stack may be correspondingly increased or varied and thus the required heating of the regenerator may be secured under the varying conditions of the run. And the temperature of the air regenerator may be controlled independently of the temperature of the gas regenerator.

The valves or gates 18 and 19 may be arbitrarily operated, as for example, by means of hand wheels 18' and 19' as shown in Fig. 1, or they may also be provided with suitable connecting mechanism so as to secure any desired relative actuation with respect to the operation of the regenerator reversing valve.

One of the reversing valves may be used to control the operation of the gates 18 and 19, providing direct connection to the stack for the air regenerators by many suitable mechanical devices. Fig. 2 shows in a dia-grammatic way the well known Schild reversing valve 20, connected by the rod 23, to operate a walking beam or rocking lever 24, attached to the gates, providing direct connection to the stack for the air regenerators, and the lift of each gate valve is fixed by the position of an adjustable nut 25. It is obvious that the rods and lever may be placed to suit conditions and to give the same motion as shown in the drawing. Such an arrangement gives the same throw to the gates at each reversal, and if increased or decreased pull through the air checkers is required, this may be secured by changing the positions of the adjustable nuts.

In operation: It will be understood that the regenerators are connected to the fur-

nace, in the usual way, that is to say, the gas and air regenerators for example 1 and 3 are connected to ports delivering to and from the furnace chamber at one end or side thereof, while the air and gas regenerators 4 and 2 are similarly connected to ports at the other end or side of the furnace chamber. By the usual operation of the reversing valves the two regenerators on one side of the furnace are connected to the stack, while the two regenerators on the other side of the furnace are disconnected from the stack. The two regenerators, not connected with the stack, are connected respectively with air and gas supplies by means not shown, as such means form no part of the present invention.

Assuming, for example, that regenerators 1 and 3 are connected to the stack 10 by means of a reversing valve, such as 20, in Fig. 2, and that the ports 12 and 14 leading to regenerators 2 and 4 are connected to supplies of gas and air, we will have the usual operation as follows: The gas and air passing through the regenerators 2 and 4 receive heat therefrom and are delivered to and through their respective ports in the furnace. The combustible mixture thereby formed is burned within the furnace chamber and the resulting burnt products pass through the ports at the other end of the furnace to and through the regenerators 1 and 3 to the stack. This is the normal operation. In case however it shall be desirable to increase the flow of burnt products through a regenerator, in order to raise the temperature therein, it is possible, by the present invention, to control said flow independently of the reversing valve and also independently of the other regenerator. For example assuming that it is desirable to increase the flow of burnt products from the furnace through regenerator 3 to the stack, it is only necessary to open valve 18 to secure a direct and unobstructed flow of burnt products from the regenerator 3 to the stack, and this will be independent of the position of the reversing valve and also of the flow through regenerator 1.

What I claim is:—

1. In an open hearth furnace having the usual regenerators and reversing valve, the combination therewith of means for establishing, when required, a direct flow of burnt products from a regenerator to the stack independently of the reversing valve.

2. In an open hearth furnace, the combination of regenerators, a reversing valve and means for establishing a by-pass between a regenerator and the stack and means for regulating said by-pass in order to secure and maintain the required pressure in said regenerator.

3. In an open hearth furnace, the combination of regenerators, a reversing valve

and means for establishing a by-pass between a regenerator and the stack, means for regulating said by-pass and means for maintaining a constant relationship between the reversing valve and the regulating means.

4. In an open hearth furnace, the combination with regenerators and the usual reversing valve control of the regenerators, of means for controlling the flow from a regenerator to the stack either independently of or in conjunction with the reversing valve control.

5. In an open hearth furnace, the combination with the regenerators and the usual reversing valve control of the regenerators, of means for establishing a separate flow from a regenerator to the stack in conjunction with the reversing valve control.

6. In an open hearth furnace, the combination with regenerators and the usual re-

versing valve control of the regenerators, of means for establishing a by-pass flow from a regenerator to the stack in order to modify the reversing valve control.

25

7. In an open hearth furnace, in combination with regenerators and the usual reversing valve control of the regenerators, means forming a by-pass communication between a regenerator and the stack and a control therefor, adapted to operate relatively to the reversing valve operation.

30

8. In an open hearth furnace, in combination with regenerators and the usual reversing valve control of the regenerators, means forming a controlling by-pass communication between a regenerator and the stack adapted to operate either independently of or in cooperation with the reversing valve operation.
